United States Patent Office.

CHRISTIAN LINDER, OF NAUFFEN, WÜRTEMBERG.

Design No. 4,564, dated January 10, 1871.

DESIGN FOR A COAL-HOD.

The Schedule referred to in these Letters Patent and making part of the same.

To all persons to whom these presents may come:

Be it known that I, CHRISTIAN LINDER, of Nauffen, of the Kingdom, of Würtemberg, have invented or produced a new and useful and ornamental Design for a Coal-Hod; and do hereby declare the same to be described in the following specification and represented in the accompanying drawing, of which—

Figure 1 is a side elevation, and

Figure 2, a rear elevation of it.

It has a pyramidal body, A, having its axis inclined with respect to the base b rather than at right angles to it.

At each corner of the base there may be a foot, c.

A bail C may be pivoted to ears d d fixed to opposite sides of the body.

There may be a handle, D, jointed or fixed to the rear side of the body and near its bottom.

The hod at its upper end may be open, or may have a cover thereto, each of the two opposite sides terminating at top in a "cynia" or "ogee," as shown at e.

The design has reference to the body alone, and includes the pyramidal form with the oblique base and the ogee top.

I claim—

The said design for a coal-hod body, as represented and described.

CHRISTIAN LINDER.
